United States Patent Office.

RALPH S. JENNINGS, OF NEW YORK, N. Y.

Design No. 3,150, dated August 4, 1868.

DESIGN FOR A SCARF-RING.

The Schedule referred to in these Letters Patent and making part of the same.

TO ALL WHOM IT MAY CONCERN:

Be it known that I, RALPH S. JENNINGS, of New York, in the county of New York, and State of New York, have originated and designed a new Pattern for Scarf-Rings; and I do hereby declare that the following is a full, clear, and exact description of the construction and operation of the same, reference being had to the annexed drawings, making a part of this specification.

The nature of my invention consists in constructing a scarf-ring, having thereon a likeness of Honorable Horatio Seymour.

What I claim as my invention, and desire to secure by Letters Patent, is—

The design for scarf-rings herein set forth and shown.

As evidence that I claim the above, I have hereunto set my name in the presence of two witnesses.

RALPH S. JENNINGS.
